United States Patent Office.

HENRY BERGER, OF NEW YORK, N. Y.

Design No. 3,941, dated March 29, 1870.

DESIGN FOR A BUST.

The Schedule referred to in these Letters Patent and making part of the same.

To all whom it may concern:

Be it known that I, HENRY BERGER, of the city, county, and State of New York, have invented a new and original Design for Bust of Franz Liszt; and I do hereby declare the following to be a full, clear, and exact description thereof, which will enable those skilled in the art to make and use the same.

The accompanying photograph represents this design for a bust of Franz Liszt.

What I claim as new, and desire to secure by Letters Patent, is—

The design for bust of Franz Liszt, as above described.

In witness whereof I have hereunto signed my name this 18th day of February, 1870.

Witnesses: HENRY BERGER.
